Patented September 13, 1904.

UNITED STATES PATENT OFFICE.

EDWIN W. RICE, JR., OF SCHENECTADY, NEW YORK, ASSIGNOR TO
GENERAL ELECTRIC COMPANY, A CORPORATION OF NEW YORK.

CIRCUIT-PROTECTING DEVICE.

SPECIFICATION forming part of Letters Patent No. 769,961, dated September 13, 1904.

Application filed February 18, 1903. Serial No. 149,912. (No model.)

To all whom it may concern:

Be it known that I, EDWIN W. RICE, Jr., a citizen of the United States, residing at Schenectady, county of Schenectady, State of New York, have invented certain new and useful Improvements in Circuit-Protecting Devices, of which the following is a specification.

My invention relates to a device for protecting an electric circuit from the effects of a lightning or other high-potential discharge, and comprises certain novel features, which I have pointed out with particularity in the appended claims.

The invention itself, as exemplified in one of the numerous embodiments of which it is capable, I have described in detail in the following specification, which is to be taken in connection with the accompanying drawings, in which—

Figure 1 represents a plan view of a circuit-protecting device or lightning-arrester built in accordance with my invention, and Fig. 2 a side elevation of the same.

In the drawings it will be noted that the working parts of the lightning-arrester are mounted upon a supporting base or plate 1, which may be of porcelain or any other suitable material.

At 2 is indicated a resistance-rod, which may be formed of a composition of clay and some suitable conducting material—such, for example, as graphite, carborundum, or the like. At each end of the rod is arranged a series of spark-gap terminals or balls, one of these series consisting of the balls 3, 4, 5, and 6, the last mentioned being provided with a binding-post 7 for connecting one end of the lightning-arrester in circuit. The other end of the resistance-rod is similarly provided with a series of balls 8, 9, 10, and 11, the last mentioned being, like the ball 6 of the other series, provided with a binding-post 12, forming the remaining terminal of the lightning-arrester. These balls or spark-gap terminals may be formed of brass or other suitable metal and may be arranged in two series, as shown, one on either side, so to speak, of the resistance-rod 2, or, if preferred, one series

only may be employed. Connection is made between the balls 3 and 8 and the adjacent ends of the resistance-rod 2, near which they are located, by clips 13 14, electrically connected with the respective spark-gap terminals or balls 8 and 3.

A series of rings 15, which may be split, are sprung about or shrunk upon the resistance-rod 2 at intervals in the length thereof, so that each ring is separated from its neighbor by a space, as indicated. These rings, which may be of brass, copper, or the like, form spark-gap terminals.

In connecting up the lightning-arrester or protecting device one terminal is connected to the line to be protected and the other to ground. In case a relatively small discharge passes through the arrester the flow of current takes place across the spark-gaps formed between the two sets of spark-gap terminals 3 to 6, inclusive, and 8 to 11, inclusive, the circuit of the discharge being completed through the resistance-rod 2. The resistance of this rod is such that it limits the value of the dynamo-current following a lightning or other high-potential discharge to such a value that the arc-extinguishing action of the series of spark-gap terminals mentioned is sufficient to interrupt the flow of current. In case a heavy discharge of excessive intensity takes place the path of the discharge instead of following the resistance-rod 2 extends mostly along the series of rings 15 from ring to ring. As soon, however, as the dynamo-current starts in response to the path opened up by the high-potential discharge it flows not from ring to ring on the resistance-rod, but passes instead through the better path afforded by the rod itself. The current thus deserting the rings 15, the arcs between the rings are immediately extinguished, and the current being reduced in value by the resistance 2 is interrupted through the arc-extinguishing action of the lightning-arrester balls in circuit with the rod 2, as above described. The lightning-arrester, as thus described, therefore furnishes a ready path for high-potential discharges and operates to interrupt the flow of current resulting from these dis-

charges whether the discharge be heavy or relatively light.

What I claim as new, and desire to secure by Letters Patent of the United States, is—

- 5 1. The combination of a plurality of spark-gap terminals, and a unitary body of high-resistance material having a series of points in the length thereof electrically connected respectively to said spark-gap terminals.
- 10 2. The combination of a rod of resistance material, spark-gap terminals arranged so as to form a circuit therewith, and metallic spark-gap terminals secured at intervals to said rod.
- 15 3. In a lightning-arrester, the combination of a rod of high-resistance material, and metallic spark-gap terminals secured at intervals to said rod.
4. In a lightning-arrester, the combination

of a rod of resistance material, and a plurality of metallic rings secured to said rod and separated from each other.

5. In a lightning-arrester, the combination of a rod of high-resistance material, and rings of low-resistance material secured to said rod and separated from each other.

6. In a lightning-arrester, the combination of a plurality of spark-gap terminals, a rod of resistance material in circuit therewith, and a plurality of rings of conducting material secured to said rod at intervals in the length thereof.

In witness whereof I have hereunto set my hand this 16th day of February, 1903.

EDWIN W. RICE, JR.
